Primary Examiner — Barbara Fox*Assistant Examiner* — Aram Kwon(74) *Attorney, Agent, or Firm* — Faegre Drinker Biddle & Reath LLP(57) **CLAIM**

The ornamental design for an amplifier, as shown and described.

DESCRIPTION

FIG. 1 is a perspective view of an amplifier showing my new design;
FIG. 2 is a front view thereof;

FIG. 3 is a top view thereof;

FIG. 4 is a bottom view thereof;

FIG. 5 is a right side view thereof; and,

FIG. 6 is a left side views thereof.

The broken lines shown in the drawings depict portions of the amplifier that form no part of the claimed design.

1 Claim, 6 Drawing Sheets(56)
